UNITED STATES PATENT OFFICE.

FELIX H. McCANN, OF NEW YORK, N. Y.

DESIGN FOR A SHRINE.

40,857.

Specification for Design.

Patented Sept. 6, 1910.

Application filed June 21, 1910. Serial No. 568,225. Term of patent 7 years.

To all whom it may concern:

Be it known that I, FELIX H. McCANN, a citizen of the United States, residing at New York, in the county and State of New York, have invented a new, original, and ornamental Design for a Shrine, of which the following is a specification, reference being had to the accompanying drawing, forming part thereof, wherein the figure represents a front elevation of the design.

I claim:

The ornamental design for a shrine, as shown.

FELIX H. McCANN.
